UNITED STATES PATENT OFFICE.

JEREMIAH A. PAIGE, OF BOSTON, MASSACHUSETTS, ASSIGNOR TO WILLIAM F. MOOERS,
OF MILTON, MASSACHUSETTS.

TROLLEY.

1,195,850.

Specification of Letters Patent. Patented Aug. 22, 1916.

Application filed April 17, 1916. Serial No. 91,698.

To all whom it may concern:

Be it known that I, JEREMIAH A. PAIGE, a citizen of the United States, residing at Boston, in the county of Suffolk and State of Massachusetts, have invented certain new and useful Improvements in Trolleys; and I do declare the following to be a full, clear, and exact description of the invention, such as will enable others skilled in the art to 10 which it appertains to make and use the same.

This invention relates to improvements in trolleys for street cars and the like, and the object is to provide a simply constructed 15 trolley harp of improved construction which is provided with means adapted to normally keep the trolley wheel in the plane of the axis of the pole, but adapted to permit the harp to oscillate to a limited extent when the 20 car is moving around curves.

With this general object in view, my invention resides in the novel features of construction, combination and arrangement of parts which will hereinafter be more particularly described and claimed.

In the accompanying drawings: Figure 1 is a side elevation of my improved trolley; Fig. 2 is a central vertical longitudinal section; Fig. 3 is a vertical section on the line 30 3—3 of Fig. 2; Figs. 4 and 5 are horizontal sections taken respectively on the planes of the lines 4—4 and 5—5 of Fig. 2; Fig. 6 is a view similar to Fig. 5, but showing the parts in slightly different positions; Fig. 7 is a vertical section on the line 7—7 of Fig. 2; Fig. 8 is a perspective view of the U-shaped brace detached; and, Fig. 9 is a detail perspective view of the lower portion of the trolley harp.

Referring more particularly to the drawings it will be seen that the numeral 1 designates the hollow upper end of a trolley pole in which a shank 2 extends from the head 3 of my improved trolley, the shank 45 being secured in the pole by any preferred means. The shank 2 is formed directly with a casting having a depending arm 4 and an upwardly extending guard portion 5 which will hereinafter be more particularly 50 described. A casing 6 which forms a portion of the head 3 is secured to the lower end of the arm 4 by means of the angular brace members 4', rivets 7 or the like being used to secure the braces thereto. The 55 upright wall 6' of the casing 6 is formed by

bending a single strip of metal into circular formation as shown in Fig. 5, the free ends of the strip being extended radially as shown at 8, these ends 8 being in contact with each other and disposed in a slot 9 in the end of the arm 4. The rivets 7 which extend through the brace members 4' and the arm 4, also extend through the end 8 of the strip of metal which forms the wall of the casing 6. The bottom of the casing is formed by a 60 circular plate 10 which is secured thereto by any preferred means and has a cylindrical bearing 11 depending from the center thereof. The upper end of this cylindrical bearing is secured in said plate 10 while its other 65 end is supported by a U-shaped brace 12 whose free ends are secured to the inner side of the upright wall 6' of the casing 6. Within the bearing 11 a shaft 13 is rotatably mounted and has a trolley harp 14 fixed to 70 its upper end, a wheel 15 being disposed within the arms 16 of said harp. The harp also includes a base plate 18 which forms a cover for the casing 6. The intermediate 75 portions of said shaft are flattened as shown at 19 on opposite sides, and the base plate of the harp is provided with an elongated opening to receive the free end of the flattened portion of the shaft 13, so that said harp will rotate therewith. The harp is securely 80 clamped to said shaft by means of a nut 20 which is threaded upon the extreme upper end of the shaft 13. By providing a trolley harp which is pivotally mounted upon a 85 head secured to the end of the trolley pole, the trolley wheel is permitted to readily follow the wire around very sharp curves without danger of its leaving the same. In order, 90 however, to quickly return the harp with its wheel to its normal position in the plane 95 occupied by the trolley pole, spring means are provided within the casing 6. As hereinbefore mentioned, the free ends of the arms of the U-shaped brace 12 are connected to the inner side of the wall 6' of the casing, 100 but before so securing them, they are bent upon themselves as shown at 21 in Fig. 8. This arrangement provides a very strong brace and also permits the same to be used as a support for holding the leaf springs 22 105 which actuate the trolley harp through the rotatable shaft 13. The ends of these leaf springs are disposed in slots 23 formed in the bent over portions 21 of the brace 12.

Although I have shown but a single pair 110

of springs secured to one side of the casing, it is obvious that an additional pair may be secured to the opposite side in a like manner, or one secured to each side. Whatever arrangement is used for mounting the springs, one is disposed on each side of the shaft 13 and adapted to coact with the flattened portion 19. In order to increase the contact surface which is engaged by the springs 22, a finger 24 in the form of a U-shaped piece is secured by its arms to the shaft 13 as shown in Fig. 5. The springs 22 are formed of several very thin leaves not only to facilitate their insertion into the slots 23, but to also allow the shaft to be operated with greater smoothness.

In addition to providing springs for returning the harp to its normal position, it is also expedient to provide stops to limit the rotation of the shaft 13 in either direction. This is accomplished in a very simple manner by securing a flat plate 25 of a length slightly less than the diameter of the casing 6 to the shaft 13 below the springs 22, which, when the shaft is rotated, abuts the portions 21 of the brace 12. One edge of the plate 25 comes in contact with one of the portions 21, while the opposite edge engages the other, so that the rotation of the shaft is positively limited.

From the foregoing description it will be seen that the ends of the brace 12 which supports the cylindrical bearing 11 not only serve as supports for holding the springs 22, but also form stops to coöperate with the moving plate 25 to limit the rotation of the shaft 13.

It is obvious that this simply constructed trolley will be much superior to the usual devices of this character now on the market, and that because of its strong construction, will seldom get out of order. After it has been secured to the end of the trolley pole, and the trolley wheel engaged with the wire, the same will readily follow the wire around practically any curve without jumping therefrom, and the harp being moved against the tension of the springs 22 will be effectively returned to its normal position by said springs when the car starts to run a straight track. However, should the wheel leave the trolley wire for any reason, the guard 5 will prevent any cross or guy wires from catching beneath the wheel 15 and thus injuring the device, it being evident that such cross wires will be conducted by the guard over the top of the trolley wheel.

I claim:

1. In a trolley, a head to be secured to the end of a pole, a shaft rising therefrom and rotatably mounted therein, a harp keyed to said shaft, a trolley wheel in said harp, and leaf springs disposed on opposite sides of said shaft and secured by one end to said

head, the opposite sides of said shaft being flattened and engaged by said springs.

2. In a trolley, a head to be secured to the end of a pole, a shaft rising therefrom and rotatably mounted therein, a harp keyed to said shaft, a trolley wheel in said harp, a finger formed of a U-shaped member secured by its arms to said shaft, and leaf springs disposed on opposite sides of said shaft and secured by one end to said head, 70 said springs engaging said finger to return said harp to its normal position after being rotated.

3. In a trolley, a head to be secured to the end of a pole, a shaft rising therefrom and rotatably mounted therein, the opposite sides of said shaft being flat, a finger extending from the shaft and having its sides secured to said flattened portions, a harp keyed to said shaft, a wheel in said harp, 85 leaf springs disposed on opposite sides of said shaft and secured by one end to said head, said springs contacting with said finger, a stop, and a plate fixed to the shaft and adapted to contact with said stop to limit 90 the rotation of said harp.

4. The combination with a trolley pole; of an arm extending therefrom, a casing having its upright wall formed from a single strip of metal bent into circular form and 95 having its ends extended radially therefrom and secured to said arm, a bottom for said casing, a rotatably mounted trolley harp comprising a base plate forming a cover for said casing, and a pair of arms, a wheel between said arms, and means within said casing to return said harp to its normal position after being rotated.

5. The combination with a trolley pole; of an arm extending therefrom, a casing having 105 its upright wall formed from a single strip of metal bent into circular form and having its ends extended radially therefrom and secured to said arm, a bottom for said casing, a rotatably mounted trolley harp comprising a 110 base plate forming a cover for said casing, and a pair of arms, a wheel between said arms, and angle braces secured to the opposite sides of the upright wall of said casing by one end and by their opposite ends to 115 said arm.

6. In a trolley, an arm to be secured to the end of a pole, a casing carried by said arm, a bottom for said casing, a bearing formed in said bottom, a brace for supporting said bearing secured by its opposite ends to the wall of said casing, a shaft rotatably mounted in said bearing, a trolley harp fixed to said shaft, a wheel rotatably mounted in said harp, and means within said casing to 125 return said harp to its normal position after being rotated.

7. In a trolley, an arm to be secured to the end of a pole, a casing carried by said arm, a bottom for said casing, a bearing formed 130

in said bottom, a brace for supporting said bearing secured by its opposite ends to the wall of said casing, a shaft rotatably mounted in said bearing, a trolley harp fixed to 5 said shaft and comprising a base plate forming a cover for said casing, and a pair of arms, a wheel rotatably mounted between said arms, and means within said casing to return said harp to normal position after 10 being rotated.

8. In a trolley, an arm to be secured to the end of a pole, a casing carried by said arm, a bottom for said casing, a bearing formed in said bottom, a brace for supporting said 15 bearing, a shaft rotatably mounted in said bearing, a trolley harp fixed to said shaft, a wheel rotatably mounted in said harp, a pair of springs secured to the walls of said casing and disposed one on each side of said 20 shaft and contacting therewith to return the same to its normal position after being rotated, the opposite sides of said shaft being flattened.

9. In a trolley, an arm to be secured to the 25 end of a pole, a casing carried by said arm, a bottom for said casing, a bearing formed in said bottom, a brace for supporting said bearing secured by its opposite ends to the wall of said casing, a shaft rotatably mounted 30 in said bearing, a trolley harp fixed to said shaft and comprising a base plate forming a cover for said casing, and a pair of arms, a wheel rotatably mounted between said arms, and springs secured to one end of 35 said brace, one of said springs being disposed on each side of said shaft and contacting therewith.

10. In a trolley, an arm to be secured to the end of a pole, a casing carried by said 40 arm, a bottom for said casing, a bearing formed in said bottom, a shaft rotatably mounted in said bearing, a brace for supporting said bearing, the opposite ends of said brace being bent upon themselves and 45 secured to the wall of said casing, one of

said bent over portions being slotted, springs disposed in said slots and extended one on each side of said shaft, said springs contacting with said shaft to return the same to its normal position after being rotated, a 50 trolley harp fixed to said shaft, and a wheel rotatably mounted in said harp.

11. In a trolley, an arm to be secured to the end of a pole, a casing carried by said arm, a bottom for said casing, a bearing 55 formed in said bottom, a brace for supporting said bearing secured by its opposite ends to the wall of said casing, a shaft rotatably mounted in said bearing, a trolley harp fixed to said shaft and comprising a base plate 60 forming a cover for said casing, and a pair of arms, a wheel rotatably mounted between said arms, and an arm fixed to said shaft and adapted to contact with the ends of said brace to limit the rotation thereof in either 65 direction.

12. In a trolley, an arm to be secured to the end of a pole, a casing carried by said arm, a bottom for said casing, a bearing formed in said bottom, a shaft rotatably 70 mounted in said bearing, a brace for supporting said bearing secured by its opposite ends to the wall of said casing, one of said ends being slotted, springs disposed in said slotted end and extended one on each side of 75 said shaft to return the same to its normal position after being rotated, an arm fixed to said shaft and adapted to contact with the ends of said brace to limit the rotation of said shaft in either direction, a trolley harp 80 fixed to said shaft, and a wheel rotatably mounted in said harp.

In testimony whereof I have hereunto set my hand in presence of two subscribing witnesses.

JEREMIAH A. PAIGE.
